DISPLAY BOX

Vincenzo Pomodoro, Villaguardia, Italy, assignor to
Neotis S.p.A., Como, Italy

Filed June 24, 1969, Ser. No. 17,848

Claims priority, application Italy Feb. 10, 1969

Term of patent 7 years

Int. Cl. D9—04

U.S. Cl. D9—184

FIG. 1

FIG. 2

FIG. 1 is a perspective view of a display box showing my new design in closed position; and

FIG. 2 is an exploded perspective view, the two parts being substantially identical to one another and the back faces thereof being ornamented the same as the front illustrated faces.

I claim:

The ornamental design for a display box, as shown and described.
